TRUNNION ADJUSTABLE SUPPORT

Edward J. Langer, Portland, Oreg.

Application February 18, 1932. Serial No. 593,825

3 Claims. (Cl. 16—44)

My invention relates to adjustable and compressible trunnion supports to be used upon furniture, bedsteads, safes, garage doors, and the like.

5 The invention is comprised primarily of a cylinder having one or more brackets associated therewith to adapt the same for being removably secured to any suitable object to be supported. A ball bearing trunnion wheel is associated with 10 the base and is adapted for being cushioned upon a compressible reacting element as a coil spring. Means being associated therewith to adapt the cushion to meet the requirements of use.

One of the objects of my invention is to construct 15 a trunnion support that is of simple design, one that may be easily and cheaply constructed and one that will have a long and useful life.

A still further object of my invention consists 20 in so constructing the device that it will have freedom to movement when in use. The assembly may be easily adjusted to meet the requirements of the service with which the same is to be used.

25 A still further object of my invention consists in so constructing my device that it will comprise a minimum number of parts that are constructed and made from standard materials.

With these and incidental objects in view, the 30 invention consists in certain novel features of construction and combination of parts, the essential elements of which are set forth in the appended claims, and a preferred form of embodiment of which is hereinafter shown with reference to the drawing which accompanies and forms 35 a part of this specification.

In the drawing:

Fig. 1 is a front view, of the assembled device.

40 Fig. 2 is a sectional, longitudinal, front view, of the assembled device.

Fig. 3 is a sectional, end view, of the assembled device. The same being taken on line 3—3 of Fig. 1, looking in the direction indicated.

45 Fig. 4 is a fragmentary, sectional, side view, of the assembled device. The same being made and comprised of the lower end of the threaded shank that is adapted for adjusting the compression, or set, within the reacting element.

50 Fig. 5 is a fragmentary, sectional, side view, of the caster or trunnion stem, which is shown in registry engagement with the lower end of the cushion plate and upon which the reacting element, as the coil spring comes to rest.

55 Fig. 6 is an inverted, plan view, of the plate upon which the coil spring is made to come to

rest and illustrating the same as being welded to the plate.

Fig. 7 is a pair of garage doors. A pair of my supports are shown associated therewith and shown holding the doors in full normal raised 60 position.

Like reference characters refer to like parts throughout the several views.

I preferably make my device of a barrel 1. The barrel is made of any suitable cylindrical material as pipe. Brackets 2 and 3 are secured to the one side of the pipe. The brackets having fastening holes 4 and 5 in the oppositely disposed ends to facilitate the fastening of the assembly to the material for holding the assembly in place 70 upon the object to be supported. I thread the upper end 6 of the barrel to facilitate the securing of a cap closure 7 thereto.

A trunnion caster support 8 forms the base of the assembly and a trunnion wheel 9 is secured to 75 the trunnion wheel support and is rotatably supported upon an axle 10. A secondary barrel 11 is slidably disposed within the primary barrel 1 and the barrel 11 is secured to the head 12 of the trunnion wheel assembly. Ball bearings 13 80 are disposed between the base and the head.

A reacting element, as a coil spring is disposed within the primary, barrel 1. The oppositely disposed ends of the coil spring are secured to plate discs 15 and 16, the same are preferably welded 85 thereto, as illustrated at 17 in Fig. 6. An adjusting screw 18 is threadably secured to the cap 7.

A central opening 18 is disposed within the plate 16 and the same has a screw thread formed 90 therein. The inner lower end of the threaded screw 18 has a screw thread 20 disposed thereupon to adapt the same for being threaded into the disc 16. A neck 19 is disposed between the body of the screw 18 and the threaded portion 20. 95 When it is found desirable to permit the rotation of the threaded stem relative to the disc 16 to compress the compressible element, the threaded screw 18 is threaded through the disc 16. The primary cross sectional area of the body of the 100 threaded screw 18 is substantially larger than the hole disposed within the disc 16 to form a shoulder that normally comes to rest upon the surface of the disc 16 when the same is threaded therethrough. A boss 22 is disposed upon the 105 upper end of the cap 7 and the screw 18 is in threaded relationship with the boss 22. A dust cap 23 is adapted for being threadably secured to the outer surface of the boss 22.

The stem 24 of the caster, or trunnion up- 110

wardly extends through the secondary barrel 11. An opening 25 is disposed within the disc 15. The opening is threaded to permit the threaded end 26 of the stem for being threadably secured to the disc, or for being passed therethrough to permit the neck 27 of the stem being freely rotated relative to the disc 15. The cross sectional area of the stem 24 is substantially larger than the opening 25 in order that the stem may come to rest upon the disc 15.

It will thus be seen that I have provided an assembly that is made quite largely of stock materials. The device is of simple construction. It may be assembled within a pipe and the cushioning effect of the reacting element may be adjusted and initially set for being calibrated to meet the requirements for the trade in which my device is adapted for being placed. The same may be used for a support for table legs, furniture, for beds, safes, garage doors and for use in any and all places where the thing to be supported is adapted for being placed and otherwise supported upon uneven surfaces.

The corners of the meeting edges of the doors being normally expected to drop down and sag, I have illustrated in Fig. 7 a pair of my trunnion supports 29 and 30 secured to the edge of the door to adapt the same for being held in full raised position.

While the form of mechanism herein shown and described is admirably adapted to fulfill the objects primarily stated, it is to be understood that it is not intended to confine the invention to the one form of embodiment herein shown and described, as it is susceptible of embodiment in various forms, all coming within the scope of the claims which follow.

What I claim is:

1. In a device of the class described the combination of a primary barrel adapted to be secured to a door at the bottom thereof, a secondary barrel rotatably and slidably mounted within the primary barrel and having its lowermost end extending below the bottom end of the primary barrel, said secondary barrel having a trunnion wheel associated therewith by means of a supporting stem adjustably mounted through the top of said secondary barrel, a coil spring disposed within the primary barrel and having one

50

of its ends bearing against the top of said secondary barrel and its opposite end bearing against a disc slidably mounted within the primary barrel and carried by an adjusting screw threadably mounted through a closure cap adapted to the top of said primary barrel, and a dust cap threadably mounted to the closure cap for housing the threaded stem.

2. In a device of the class described the combination of a primary barrel adapted to be secured to the outer surface of a door at the bottom thereof, a secondary barrel adjustably carrying a trunnion wheel adapted to yieldingly contact the floor below the door, a coil spring disposed within the barrel and having one of its ends bearing against the top of the secondary barrel and its opposite end bearing against the disc carried by an adjusting screw threadably extending through a closure cap for the primary barrel and into a dust cap secured thereto, and means disposed near the end of the stem or threadedly disengaging said disc from the lowermost end of the stem for allowing a shoulder portion of the stem to come into wiping contact with said disc.

3. In a device of the class described, the combination of a primary barrel formed with supporting brackets and adapted to be secured to a door at the bottom thereof, said primary barrel being open at its lower end and closed at its upper end by a closure cap having an internally threaded aperture therethrough, a hollow secondary barrel closed at its upper end and slidably and rotatably mounted within the primary barrel and normally extending beyond the lowermost end thereof, an apertured and threaded disc superposed upon the upper end of the secondary barrel, a threaded stem extending downwardly through the closure cap and provided at its lowermost end with a disc, a coil spring disposed within the primary cylinder and having one of its ends bearing against said disc and its opposite end against the disc carried by said secondary cylinder, a trunnion wheel associated with said secondary cylinder by means of a supporting shaft extending upwardly through the cylinder and beyond the uppermost end thereof.
